UNITED STATES PATENT OFFICE.

HARRY J. MOREY, OF SYRACUSE, NEW YORK, ASSIGNOR TO PASS & SEYMOUR, INC., OF SYRACUSE, NEW YORK, A CORPORATION OF NEW YORK.

PULL SOCKET.

Application filed October 13, 1924. Serial No. 743,487.

This invention relates to sockets for incandescent lamps and more particularly to those sockets having a self-contained switch for controlling the current to the lamp.

- 5 It is an object of this invention to provide in a switch socket means for placing the switch operator at the same potential as one of the current carrying wires supplying current to the lamp.
- 10 It is a further object of this invention to provide in a switch socket means for placing the metallic shell thereof at the same potential as one of the wires conducting current to the lamp.
- 15 A still further object of this invention is to provide, in a pull chain socket for incandescent lamps, means for electrically connecting the chain guide to one of the current conducting wires within the socket.
- 20 In the accompanying drawings and in the following specification is disclosed one embodiment of the invention, with the understanding that various changes and modifications in size, proportion and arrangement 25 of elements may be made without departing from the spirit of the invention as expressed in the attached claims.

In said drawings:

- 30 Figure 1 is a side elevation of a socket constructed according to this invention;
- Figure 2 is a side elevation of the socket with the shell and cap removed;
- Figure 3 is a transverse section on line 3—3 of Figure 2 showing the shell in position;
- 35 Figure 4 is a perspective view of one of the binding terminals and its associated parts;
- Figure 5 is a perspective view of the chain guide;
- Figure 6 is a section on line 6—6 of Fig. 3;
- 40 and
- Figure 7 is a view similar to Fig. 2 but with the insulating sleeve in position.

When the ordinary form of electric socket, having a switch incorporated therein, is used in medium potential circuits, there is often danger of the person operating the switch receiving a shock, especially if at the same time they are standing on, or touching, a metallic object, such as a water pipe, steam radiator, or standing on wet ground. In order to obviate this difficulty, it has been required in some States that the fixture upon which the socket is mounted be connected to ground. Other States require the fixture to be permanently insulated from ground. The appli-

cant has found, however, that the most satisfactory solution of the problem consists in the use of the usual two wire distributing system, one wire of which is permanently at ground potential, either at the generating 60 station or at one of the distributing transformers where alternating current is used. This wire is then connected by means of the device of this invention to the switch handle or operator and also to the shell of the socket, 65 and thus all exposed metal portions of the socket and the fixture to which it is attached are permanently placed at ground potential and at the potential of one of the wires of the circuit. Preferably and conveniently this 70 grounded wire is attached to the screw shell of the socket, since it is this shell which contacts with the exposed portion of a lamp base when it is being placed in position in a socket.

75 Reference to the drawings discloses a common form of pull chain socket enclosed within the tubular metallic shell 10 and covered by the cap 11, by means of which it may be attached if desired to a fixture. The shell 80 10 and the cap 11 are lined with an insulating sleeve 12 formed of fiber or other suitable material, and fitting tightly therein is the main portion of the socket 13 comprising the spaced insulating buttons 14 and 15 housing 85 between them and serving to support the pull chain switch mechanism 16 of any convenient or well known type. The insulating button 15 has supported thereon and insulated thereby from each other the two contacts for the 90 lamp, the center contact 16 being connected to one pole of the switch and the screw shell contact 17 being connected directly to one of the binding terminals of the socket.

95 The insulating buttons 14 and 15 are preferably formed of porcelain or other suitable insulating material and are held in position and spaced apart by means of the two binding terminals 18 and 19 composed of U-shaped straps of sheet metal, having the 100 arms of the U suitably secured to the buttons and being electrically connected respectively with one of the switch terminals and with the screw shell. Each of these binding terminals carries a suitable binding screw 105 18'—19' adapted to engage and retain in contact therewith one of the wires of the circuit carrying current to the lamp.

The binding terminal 18 is of the usual construction as described, but the binding 110

terminal 19 is adapted not only to support the chain guide 20 but also to electrically connect it to one of the wires leading to the socket. For this purpose, the parallel arms 21 and 22 of the binding terminal which are fastened to the insulating buttons are cut away as shown at 23 to provide the arcuate recesses which are adapted to receive and tightly hold therein the curved arms 24 on the base 25 which supports the conical chain guide 20. The center portion 26 of the binding terminal 19 is provided with the slots 27 through which the ends 28 of the arms 24 are adapted to pass to securely clamp these arms in position and prevent their direct withdrawal from the slots 23. However, by rotating the whole chain guide in a counter-clockwise direction, as viewed in Figure 5, it may be readily removed from engagement with the binding terminal. This engagement forms the sole support for the chain guide, and the depending lip 29 thereon prevents clockwise rotation when it engages against the outer edge of the lower button 15. An extended arm 30 provides a support for the binding screw to connect a wire to the terminal 19. It will be seen that the mechanical engagement between the chain guide and the binding terminal provides also an electrical connection between these two parts and thus serves to place the chain guide and the chain which passes through it at the same potential as one of the wires leading to the socket, which, as previously explained, 35 should be grounded.

In order to place the socket shell at the same potential as the chain guide, the insulating lining is cut away along the edges of the chain guide slot in the shell as shown at 31, in order that the metal adjacent the slot may be pressed down into engagement with the plate 25 of the chain guide when the cap 11 is pressed on and compresses the end of the shell, which construction is best 45 illustrated in Figure 3.

From the foregoing it will be evident that this invention provides a novel, simple and convenient means for placing the switch operator, which may be a chain, key, push button, or any other of the various types, in electrical connection with a grounded wire in the circuit leading to the lamp, and which also provides an effective means for placing the shell of the socket at the same potential, 55 and thus removes the possibility of the person using the socket of obtaining a shock.

Having thus described my invention what I claim as new and desire to secure by U. S. Letters Patent is:

60 1. A socket for an electric lamp, including in combination, a conductive enclosing shell, a contact shell therein for the lamp, an insulating sleeve between said shells, a second contact for the lamp, a binding screw for each contact adapted to receive a conductor,

and means to electrically connect one of said contacts to said enclosing shell.

2. A socket for an electric lamp, including in combination, a conductive enclosing shell, a contact shell therein for the lamp, a second contact for the lamp, a binding screw for each contact adapted to receive a conductor, and means to electrically connect said contact shell to said enclosing shell. 70

3. A socket for an electric lamp, including in combination, an enclosing shell, a contact shell therein for the lamp, a second contact for the lamp, a binding screw for each contact adapted to receive a conductor, a switch interposed between one of said contacts and its binding screw, an operator therefor adapted to pass through said enclosing shell, and a guide for said operator electrically connected to one of said binding screws. 75

4. A socket for an electric lamp, including in combination, a conductive enclosing shell, a contact shell therein for the lamp, a second contact for the lamp, a binding screw for each contact adapted to receive a conductor, a switch interposed between one of said contacts and its binding screw, an operator therefor adapted to pass through said enclosing shell, a guide for said operator electrically connected to one of said binding screws, and means to cause electrical connection between said guide and said enclosing shell. 80

5. A socket for an electric lamp, including in combination, a conductive enclosing shell, an insulating lining therefor, a pair of spaced insulating buttons therein, a screw shell and a center contact carried by one of said buttons, pull chain switch structure between said buttons, binding terminals adapted to receive current carrying wires and each associated with one of said contacts on said button, a chain guide electrically and mechanically connected to one of said binding terminals, and an electrical connection between said chain guide and enclosing shell. 100

6. A socket for an electric lamp, including in combination, a conductive enclosing shell, an insulating lining therefor, a pair of insulating buttons therein, binding terminals connecting and spacing said buttons, a screw shell and center contact for a lamp carried by one of said buttons, a pull chain switch between said buttons and interposed between one of said binding terminals and said center contact, a connection between said other binding terminal and said screw shell and a chain guide electrically connected to said other binding terminal. 115

7. A socket for an electric lamp, including in combination, a conductive enclosing shell, an insulating lining therefor, a pair of insulating buttons therein, binding terminals connecting and spacing said buttons, a screw shell and center contact for a lamp carried by one of said buttons, a pull chain switch 120

between said buttons and interposed between one of said binding terminals and said center contact, a connection between said other binding terminal and said screw shell and a chain guide electrically connected to and supported by said other binding terminal.

8. A socket for an electric lamp, including in combination, a conductive enclosing shell, an insulating lining therefor, a pair of insulating buttons therein, binding terminals connecting and spacing said buttons, a screw shell and center contact for a lamp carried

by one of said buttons, a pull chain switch between said buttons and interposed between one of said binding terminals and said center contact, a connection between said other binding terminal and said screw shell and a chain guide electrically connected to said other binding terminal, said chain guide adapted to electrically contact with said enclosing shell. ¹⁵ ²⁰

In testimony whereof I hereunto affix my signature.

HARRY J. MOREY.
